UNITED STATES PATENT OFFICE.

AUGUST G. BRUTSCHER, OF PITTSBURGH, PENNSYLVANIA.

HAT-PIN-POINT PROTECTOR.

1,049,806.

Specification of Letters Patent.

Patented Jan. 7, 1913.

Application filed January 27, 1912. Serial No. 673,937.

To all whom it may concern:

Be it known that I, AUGUST G. BRUTSCHER, a citizen of the United States of America, residing at Pittsburgh, in the county of Allegheny and State of Pennsylvania, have invented certain new and useful Improvements in Hat-Pin-Point Protectors, of which the following is a specification, reference being had therein to the accompanying drawing.

This invention relates to a hatpin point protector, and the primary object of my invention is to provide a guard and lock that can be easily and quickly mounted upon the pointed end of a pin and clamped thereon, whereby the guard cannot become accidentally displaced.

A further object of this invention is to provide a hatpin point protector that is susceptible to any desired ornamentation and which will lock a hatpin in a hat, besides preventing pedestrians from being injured by contacting with the pin.

With the above and other objects in view, the invention resides in the novel construction, combination and arrangement of parts to be hereinafter specifically described and then claimed.

Reference will now be had to the drawing, wherein:—

Figure 1 is a side elevation of a hatpin provided with a guard in accordance with this invention, Fig. 2 is an enlarged longitudinal sectional view of the guard, as mounted upon the pointed end of a pin, Fig. 3 is a similar view showing a portion of a detached guard, and Fig. 4 is a front elevation of the same.

A guard in accordance with this invention comprises a sleeve 1 adapted to receive the pointed end 2 of a hatpin. The sleeve 1 has one end thereof provided with an ornamental head 3 and the opposite end of the sleeve has diametrically opposed walls thereof slotted, as at 4 approximately two-thirds the length of the sleeve, the slits of said sleeve providing resilient semi-cylindrical arms 5 and 6 of greater thickness at one end thereof than at the opposite end, the increased thickness of the arms increasing the gripping power of the same relatively to

the pointed end of a pin. The end of the arm 6 is provided with a funnel-shaped mouthpiece or entrance member 7 that acts as a guide in centering the pointed end of the pin 2 to enter the sleeve 1. Prior to mounting the head 3 upon the end of the sleeve 1, a barrel-shaped member 8 is slidably mounted upon the sleeve and with the member in proximity to the funnel-shaped mouthpiece 7, the resilient arms 5 and 6 are compressed and clamped upon the pointed end 2 of the pin. With the member 8 in engagement with the head 3, the arms 5 and 6 are released and the pointed end of the pin can be easily withdrawn from the sleeve 1.

In manufacturing the device two methods can be resorted to. First, that of providing the sleeve with a flared end to form the funnel-shaped mouthpiece 6, then transversely slitting the funnel-shaped mouthpiece, as at 9 and then longitudinally slitting the sleeve 1 as indicated at 4, thereby releasing a portion of the sleeve to form the resilient arm 5, while the remainder of the device provides the resilient arm 6. The other method is that of making the funnel-shaped mouthpiece 7 of a separate piece of material from the sleeve 1 and then soldering or otherwise securing the funnel-shaped mouthpiece 7 to the end of the arm 6. Either of these methods is inexpensive and a durable device is provided that has the advantage of being extremely simple, positive in its action and not liable to injury by ordinary use.

It is obvious that the head 3 is susceptible to any desired ornamentation and can be finished to harmonize with the head of the pin.

What I claim is:—

A hat pin point protector comprising a head, a sleeve having one end integral with said head and further longitudinally slotted for a portion of its length to provide a pair of longitudinally extending resilient arms, said slit extending from the inner terminus of the sleeve, one of said arms of greater length than the other, said arms diverging at their outer ends, a cup-shaped mouth piece having its bottom formed with a cen-

trally disposed opening, that arm of greater length having the terminus of its flaring portion formed integral with the outer face of said mouth piece to one side of said opening, said free arm enabling said arms to be compressed together to clamp a pin therebetween, each of said arms of the same width throughout, and a tubular member

slidably mounted upon said sleeve for compressing the arms to clamp a pin thereto. 10

In testimony whereof I affix my signature in the presence of two witnesses.

AUGUST G. BRUTSCHER.
